UNITED STATES PATENT OFFICE.

JAMES M. MACDONALD, OF EAST ORANGE, NEW JERSEY.

CONTAINER.

Application filed April 17, 1926. Serial No. 102,699.

My invention relates to containers and refers particularly to containers suitable for the carrying and use of powder compacts.

The object of my invention is a device capable of containing a powder compact and a powder puff, the device being so arranged and constructed that the puff may be moved over the surface of the compact while the device is in closed position, thus preventing the spilling of loose powder and overcoming the inconvenience and uncleanliness incident to the application of the puff to the compact by direct hand application of the user.

The above described, and other valuable features of the device of my invention will be evident upon a consideration of this specification and the accompanying drawings.

In the accompanying drawings illustrating one form of the device of my invention, similar parts are designated by similar numerals.

Figure 1 is a top view of one form of the device of my invention.

Figure 2 is an edge view of Figure 1.

Figure 3 is a plan view of the device of Figure 1 in open position, partly broken away for purposes of explanation.

Figure 4 is an enlarged cross-section through the line 4—4 of Figure 1.

Figure 5 is a top view of the plunger member.

Figure 6 is a top view of the powder compact partly broken away.

Figure 7 is a top view of the annular revolving member.

Figure 8 is a top view of the supporting member.

Figure 9 is a top view of the flange member.

The particular form of the device of my invention shown in the accompanying drawings comprises an annular bottom 10, the edge of which is turned inwardly upon itself

11 and then upwardly 12. Positioned above the bottom member is a ring-shaped supporting member 13, the outer edge of which is turned downwardly at 14 and then outwardly at 15, the ring member being affixed

50 to the bottom member by solder, or otherwise. The inner edge of the ring member is turned downwardly and inwardly forming the shoulder 16 and then downwardly at 17 and inwardly at 18.

55 Positioned within the member 17 is an annular flange member having the vertical

member 19 and the inwardly extended flange 20, the members 17 and 19 being affixed to each other.

It will thus be seen that the bottom, the 60 ring-shaped member and the annular flange member are attached to each other to form a bottom member.

Positioned above the bottom member and revoluble thereon is an annular member 34 65 which is turned inwardly at 21, then downwardly and inwardly forming the shoulder 22, the two shoulders 16 and 20 thus acting as guides and retaining means for the member 34 during its revolution.

70 A cover, or lid, 23 is hingedly attached to the member 34 at 24.

Hingedly attached to the cover 23 at 25 is a catch 26, capable of closing attachment with the lip 27 carried by the member 34.

75 An annular bezel 28 retains the mirror 29 within the cover 23.

A powder compact 30 is attached to the compact base 31, which, in turn, is attached to the vertically movable plate, or plunger, 80

32, the edges of which are capable of abutment upon the lower face of the flange and which is attached to the spiral spring 33 abutting upon the inner face of the bottom 10.

85 The plunger 32 has a plurality of recesses 36, 38 into which the projection 37, 39 of the supporting member 19 are inserted to prevent the free rotation of the former.

The compact base 31 has a recess 38 into 90 which the projection 39 of the plunger is inserted to prevent the rotation of the former.

A powder puff 35 is placed between the mirror 29 and the compact 30.

95 The operation of the device is as follows:

The device is closed as shown in Figure 4 and the top member is revolved upon the bottom member, the latter being preferably held free from movement. This rotary movement of the top member carries the powder puff 35 with it, thus moving it over the face of the compact 30 and accumulating a portion of the compact powder upon the puff. The lid, or cover, 23 is then opened, the puff removed and used.

100 It will be noted that the bezel 28 presses the edge portion of the puff 35 against the member 21, thus forming a tight jointure preventing the escape of loose powder.

110 The spring 33 tends to press the compact 32 upwardly against the puff 35, thus allowing

ing of contact between the two irrespective of the wearing away of the compact.

It will also be noted, that the entire upper face of the compact is worn away uniformly.

5 A new compact with its base can be readily introduced when the old one is worn away.

My device, therefore, presents a compact container in which the powder puff may be moved over the surface of a compact to produce a uniform wear thereon, the movement being accomplished without the hand of the operator coming into contact with either the puff or the compact, means also being employed to retain loose powder within the 15 container.

I do not limit myself to the particular size, shape, number or arrangement of parts as shown and described as these are given simply as a means for clearly describing my invention.

20 What I claim is:—

1. In a powder compact container, in combination, a bottom member, a non-revoluble compact plunger within the bottom member 25 and spaced from the bottom thereof, means tending to move the plunger upwardly, means for limiting the upward movement of the plunger, and an upper revoluble member carried by the bottom member and spaced therefrom forming a powder puff receptacle.

2. In a powder compact container, in combination, a bottom member, a non-revoluble compact plunger within the bottom member 35 and spaced from the bottom thereof, means tending to move the plunger upwardly, means for limiting the upward movement of the plunger, and an upper revoluble member hingedly attached to the bottom member and spaced therefrom forming a powder puff receptacle.

3. In a powder compact container, in combination, a bottom member, an inwardly extended annular flange member carried by the side of the bottom member and spaced from 45 the bottom thereof, a non-revoluble compact plunger larger than the opening of the flange member and positioned between the flange member and the bottom of the bottom member, resilient means tending to move the plunger upwardly, a top member carried by the bottom member and revoluble thereon, a cover carried by the top member and a puff carrying compartment between the cover and the plunger.

55 4. In a powder compact container, in combination, a bottom member, an inwardly extended annular flange member carried by the side of the bottom member and spaced from the bottom thereof, a non-revoluble 60 compact plunger larger than the opening of the flange member and positioned between the flange member and the bottom of the bottom member, resilient means tending to move the plunger upwardly, a top member carried by the bottom member and revolu-

ble thereon, a cover carried by the top member, a puff carrying compartment between the cover and the plunger and means whereby a puff within the puff compartment will form a closure between the bottom member 70 and the top member when the lid is closed.

5. In a powder compact container, in combination, a bottom member, an inwardly extended annular flange member carried by the side of the bottom member and spaced 75 from the bottom thereof, a non-revoluble compact plunger larger than the opening of the flange member and positioned between the flange member and the bottom of the bottom member, resilient means tending to 80 move the plunger upwardly, a top member carried by the bottom member and revoluble thereon, a cover carried by the top member, a puff carrying compartment between the cover and the plunger and means whereby a puff within the compartment will be compressed against a powder compact carried by the plunger when the lid is closed.

6. In a powder compact container, in combination, a bottom having an upwardly 90 extended side, an inwardly extended supporting member fixedly attached to the side member, an inwardly extended ring-shaped flange member fixedly attached to by the supporting member, a vertically movable 95 non-revoluble compact plunger between the flange member and the bottom member, resilient means tending to move the plunger upwardly means limiting the upward movement of the plunger, a top member carried by and revoluble upon the combined bottom members, a hinged cover carried by the top member forming a powder puff compartment and means for maintaining the 100 cover in closed position.

7. In a powder compact container, in combination, a bottom having an upwardly extended side, an inwardly extended supporting member fixedly attached to the side member, an inwardly extended ring-shaped flange member fixedly attached to by the supporting member, a vertically movable non-revoluble compact plunger between the flange member and the bottom member, resilient means tending to move 110 the plunger upwardly, means limiting the upward movement of the plunger, a top member carried by and revoluble upon the combined bottom members, a hinged cover carried by the top member forming a powder puff compartment, means tending to move 115 the plunger upwardly, means limiting the upward movement of the plunger, a top member carried by and revoluble upon the combined bottom members, a hinged cover carried by the top member forming a powder puff compartment, means whereby a puff within the compartment will be pressed against a powder compact carried by the plunger when the cover is closed and means for maintaining the cover in closed position.

8. In a powder compact container, in combination, a bottom having an upwardly extended side, an inwardly extended supporting member fixedly attached to the side 120

member, an inwardly extended ring-shaped flange member fixedly attached to by the supporting member, a vertically movable non-revoluble compact plunger between the 5 flange member and the bottom member, resilient means tending to move the plunger upwardly, means limiting the upward movement of the plunger, a top member carried by, and revoluble upon the combined bottom members, a hinged cover carried by the top member forming a powder puff compartment, means whereby a puff within the

compartment will be pressed against a powder compact carried by the plunger when the cover is closed, means whereby a puff 15 within the compartment will form a closure between the bottom member and the top member when the cover is closed and means for maintaining the cover in closed position. 20

Signed at New York city in the county of New York and State of New York this 16th day of April, 1926.

JAMES M. MACDONALD.
